United States Patent Office.

NICHOLAS REPP, OF WATERLOO, IOWA.

Letters Patent No. 91,044, dated June 8, 1869.

IMPROVEMENT IN NAIL-CLINCHER FOR HORSESHOES.

The Schedule referred to in these Letters Patent and making part of the same.

To all whom it may concern:

Be it known that I, NICHOLAS REPP, of Waterloo, in the county of Black Hawk, and State of Iowa, have invented a new and improved Nail-Clincher for Horseshoes; and I do hereby declare that the following is a full, clear, and exact description thereof, which will enable others skilled in the art to make and use the same, reference being had to the accompanying drawings, forming part of this specification, in which—

Figure 1 represents a side view of my improved nail-clincher.

Figure 2 is a transverse section of the same, taken on the plane of the line x x , fig. 1.

Similar letters of reference indicate corresponding parts.

This invention relates to a new instrument for cutting and clinching horseshoe-nails, and for filing the hoof under the clinched parts of the nails, said instrument being intended as a substitute for the four tools heretofore used for the same object, to wit: a nail-cutter, a nail-head holder, a rasp, and a hammer for clinching.

The number of tools heretofore required made horseshoeing very inconvenient, as the blacksmith could not hold all the tools in his hand, and had frequently to change his place, especially with an unquiet horse. He therefore required an assistant, or had to release the hoof to go after his tools.

Another difficulty with the hammering of nails is, that they are frequently hammered out again, more or less, while being clinched, and thereby the shoe becomes loose while being applied.

My invention overcomes all these difficulties. It combines all the aforementioned tools in such a convenient manner as to be light and conveniently handled. It will reach a nail of any length, and at any suitable distance from the edge of the hoof, and will hold and support the head of a nail before it commences to clinch the same, so that the nail cannot be worked loose.

The rasp is removable, to be replaced when worn.

A and B, in the drawing, are the two handles of my improved clincher. They are pivoted together by means of a pin, a , and are made of malleable cast-iron, or suitable material.

On the end of one handle, A, may be formed a hook-shaped extension, b , while the other handle has a segmental toothed arm, c , formed on it, the toothed edge of the segment being eccentric to the pin a , as shown.

Near to the pivot a are secured, to both handles, cutters d d , which are dovetailed, or otherwise removably secured, and which serve to cut the nails to the proper length before they are clinched.

C is a rasp, fastened to the handle A by means of screws, e e , or otherwise, so that it can be removed or reversed at will. The rasp is used to file the hoof for the reception of the clinch, in order to bring the latter flush with the hoof.

The hook v is placed under the shoe when the handles are together, as in fig. 1, so that it will support the head of the nail, it being provided with an elevated portion, f , for better holding the nail-head. The handle B is then swung up, so as to carry the clincher c down, which will reach the nail that projects from the hoof, and will bend it over, clinching it properly.

The rasp, cutters, and the clincher, may be made of steel, or other suitable hard material.

I claim as new, and desire to secure by Letters Patent—

The improved implement, consisting of the handles A B, provided with the side-cutters d d , notched eccentric clincher c , formed in continuation of the handle B, the file C, and either with or without the hook b f , all arranged as described, for the purposes specified.

NICHOLAS REPP.
